John H. Brown
INVENTOR

UNITED STATES PATENT OFFICE

JOHN H. BROWN, OF HASKELL, OKLAHOMA

REFUSE SEPARATOR

Application filed November 22, 1930. Serial No. 497,361.

This invention appertains and relates to improvements in refuse separators for separating and removing foreign objects from a light material being transported in suction pipes, and is particularly adopted for the separating, and removing of rocks, nails, wire, pieces of iron, tin, leather and other refuse from cotton in the seed or in the lint as it passes through suction pipes from one place to another, as from the wagons to the gin.

The principal object of this invention is to remove all foreign objects from the cotton before it reaches the gin saws by a device that will be of low cost to manufacture, cheap to install, and of low cost to maintain.

By removing all rocks, metal pieces, and other refuse from the cotton before it enters the gins there will be nothing to cause sparks by coming in contact with the gin saws, thereby practically eliminating the origin of the large majority of all gin fires.

Another important advantage of this invention is that by removing all foreign objects from the cotton before it enters the gin there will be nothing to dull the gin saws.

Other important objects and advantages of the invention will readily become apparent to the reader of the following specifications.

In the drawing:—

Fig. 1 is a side view of the invention showing it in position on the suction pipe.

Fig. 2 is an end view of the invention, looking toward the left of Fig. 1.

Fig. 3 is an enlarged fragmentary transverse section on line 3—3 of Fig. 1.

Referring to the drawing wherein like numerals designate like parts, numeral 1 indicates a suction pipe used in transferring cotton or other light material by means of air drafts.

In this description the word "cotton" will be used, but the uses of the invention extend to all similar materials.

Cotton being transferred from wagons or bins travels through pipe 1, entering on the left and traveling towards the right.

Numeral 2 indicates an opening in pipe 1,

the size of which is controlled by sliding valve 3.

Numeral 3 indicates a sliding valve which has downwardly and outwardly turned side edge portions which slidably engage in hook-shaped guides 4 arranged longitudinally of and secured to the outside of pipe 1 at opposite sides of and beyond one end of opening 2.

Numeral 5 represents drop pipe connecting with pipe 1 above, and located immediately below the opening 2 in pipe 1.

Numeral 6 indicates a trap door at the bottom of the depending refuse collecting hopper or drop pipe 5, which normally closes the bottom of pipe 5 to render it practically air tight.

Numeral 7 indicates hinges attaching trap door 6 to pipe 5.

Numeral 8 indicates a lever arm attached to trap door 6.

Numeral 9 indicates a balance weight on lever arm 8, which can be adjusted by thumb screw and moved back and forth on lever arm 8 as desired.

Numeral 10 indicates a hand lever to be used in moving sliding valve 3 so as to regulate the size of opening 2.

Numeral 11 indicates a bracket to which is hinged the upper end of lever arm 10 said bracket being adapted for attachment to a ceiling or other support.

Numeral 12 indicates a link connecting lever 10 with sliding valve 3.

Cotton entering pipe 1 moves to the right taking with it any nails, rocks or other refuse. On coming to opening 2 in pipe 1, the refuse drops through opening 2 into drop pipe 5. The light cotton being pulled over opening 2 by the air pressure moves on through the pipes to the gin or other container to the right. At necessary intervals lever arm 8 is raised, opening trap door 6 and allowing the refuse in pipe 5 to drop in tub or basket for removal. Any cotton which might fall in pipe 5 can be picked from basket or tub by hand and replaced in cotton bin.

While the foregoing specification sets forth the invention in specific terms, it is to be

understood that numerous changes in the size, shape and materials may be resorted to without departing from the spirit and scope of the invention as claimed hereunder.

5 Having thus described my invention, what I claim as new is:

1. In a device for separating refuse from seed cotton, a suction pipe for conveying the cotton, said pipe having an opening in its 10 under side and guideways at opposite sides of said opening, a refuse collecting hopper depending from said pipe and communicating with the latter through said opening, a valve plate for controlling the passage of 15 refuse through said opening slidably engaged in said guideways, and means for adjusting said valve plate, said guideways being hook-shaped in section, said valve plate having outwardly and downwardly turned side marginal portions engaged in said guideways.
2. In a device for separating refuse from seed cotton, a suction pipe for conveying the cotton, said pipe having an opening in its 20 under side and guideways at opposite sides of said opening, a refuse collecting hopper depending from said pipe and communicating with the latter through said opening, a valve plate for controlling the passage of refuse through said opening slidably engaged in said guideways, means for adjusting said valve plate, said means including a lever pivoted above and straddling the suction pipe, and a link connecting the intermediate portion of said lever with one end 25 of said valve plate.

JOHN H. BROWN.
